UNITED STATES PATENT OFFICE

121,104

DESIGN FOR A COMFORT STATION

Arthur C. Stewart, Pasadena, and Kem Weber,
Los Angeles, Calif., assignors to Union Oil
Company of California, Los Angeles, Calif.,
a corporation of California

Application March 6, 1939, Serial No. 83,366

Term of patent 3½ years

To all whom it may concern:

Be it known that we, Arthur C. Stewart and Kem Weber, citizens of the United States and residing, respectively, at 3001 Lombardy Road, Pasadena, California, and at 672 So. Lafayette Park Place, Los Angeles, California, have invented a new, original, and ornamental Design for a Comfort Station, of which the following is a specification, reference being had to the drawing, forming a part thereof.

In the drawing:

Figure 1 is a front elevational view of the comfort station showing our design;

Figure 2 is a side elevational view of said comfort station; and

Figure 3 is a plan view of said comfort station. The rear and side elevations, not disclosed, are similar to the front elevation as shown in Figure 1.

We claim:

The ornamental design for a comfort station, substantially as shown and described.

ARTHUR C. STEWART.
KEM WEBER.
